UNITED STATES PATENT OFFICE.

WILLIAM M. RAPP, OF PHILADELPHIA, PENNSYLVANIA.

LINOTYPE-MACHINE.

1,029,714.

Specification of Letters Patent. Patented June 18, 1912.

Original application filed August 17, 1910, Serial No. 577,640. Divided and this application filed September 21, 1911. Serial No. 650,511.

To all whom it may concern:

Be it known that I, WILLIAM M. RAPP, a citizen of the United States, residing at Philadelphia, in the county of Philadelphia and State of Pennsylvania, have invented certain new and useful Improvements in Linotype-Machines, of which the following is a specification.

My invention relates to improvements in 10 linotype machines, and more particularly to an improved brake for the assembler slide, the object of the invention being to provide an improved brake of this character which will be of extremely simple construction, yet efficient in its normal use.

This application is a division of my application filed August 17, 1910, for linotype machines, and given Serial No. 577,640.

The invention consists in certain novel 20 features of construction and combinations and arrangements of parts as will be more fully hereinafter described and pointed out in the claims.

In the accompanying drawings: Figure 1, 25 is a view in front elevation illustrating the assembling mechanism of an ordinary linotype machine with my improvements in position. Fig. 2, is a top plan view of the mechanism shown in full lines in Fig. 1. 30 Fig. 3, is an end view, and Figs. 4, 5, and 6, are views of various details of construction.

Referring particularly to Fig. 1, a portion 35 of the frame 1, the elevator 2, and the star wheel 3 of an ordinary linotype machine are illustrated in dotted lines, and my improvements illustrated in full lines in their coöperative relation to the parts above referred to. 4, is the assembler slide which 40 is made in sections providing longitudinal slots 5 through which a guide block 6 projects to guide the sliding movement of the assembler slide, and 7 is a spring bar for drawing the slide longitudinally to its starting point with its adjustable finger 8 against star wheel 3. This assembler slide is moved in the opposite direction as the matrices 9 and spacebands 10 are assembled and moved into position between the star 45 wheel and finger 8. A toothed rack 11 is formed on the upper edge of the slide 4, and meshes with the teeth of a gear wheel 12, having rotary mounting in the plate 14. On this shaft 13, a dial 15 is secured and

spaced from the gear by means of a block 55 or sleeve 16, and this dial is provided with a scale around its periphery, beginning with zero and numbered up to twenty-nine, dividing the dial into thirty marks indicating picas.

To brake the assembler slide, I employ a 60 brake lever 33 which is pivotally supported between its ends on a screw pivot 34. One end of this lever 33 is bent upwardly and laterally as illustrated in Fig. 5, and projects into a bifurcated bracket 35, which may be of rawhide or other suitable material if desired, the two members of this bracket 35 having recesses 36 to receive the lower longitudinal member of the assembler slide to straddle the same. The opposite walls of these recesses 36 are beveled as shown, so that when the bracket is in a vertical position, its sharp edges engage the slide and hold it against retrograde movement, but when the lever 33 is pivoted so as to tilt bracket 35 slightly, the latter presents a wider surface to the slide and allows it to move rearwardly. The long end of this lever 33 is made with a bifurcated 70 bracket 37, and a lever 38 is fulcrumed between its ends on the screw pivot 34, and at one end is located in the bifurcated bracket 37. The opposite end of this lever 38 is located in the path of movement of the elevator 2, so that when the elevator moves upwardly to carry the assembled line of matrices, it will engage this lever 38, and the latter will move the bracket lever 33 so as to release the assembler slide and allow it to be drawn backward by means of the spring bar 7. This brake 33 may also be operated by hand or foot power whenever desired, and is held in normal position by a 80 spring 45.

Various slight changes might be made in 90 the general form and arrangement of parts described without departing from my invention, and hence I do not limit myself to the precise details set forth, but consider myself at liberty to make such changes and alterations as fairly fall within the spirit and scope of the appended claims.

Having thus described my invention, what I claim as new and desire to secure by Letters Patent is:

1. In combination with a linotype machine and an assembler slide, a brake lever

5 pivoted between its ends, a bifurcated bracket having notches receiving the slide, the opposed walls of said notches beveled where they engage the slide, and one end of said lever projecting into said bracket and constructed to tilt the same when the lever is moved, substantially as described.

2. In combination with a linotype machine and an assembler slide, a brake lever 10 pivoted between its ends, a bifurcated bracket having notches receiving the slide, the opposed walls of said notches beveled where they engage the slide, one end of said

lever projecting into said bracket and constructed to tilt the same when the lever is moved, the other end of said lever bifurcated, and a brake operating lever located in the bifurcated end of said brake lever, substantially as described.

In testimony whereof I have signed my name to this specification in the presence of two subscribing witnesses.

WILLIAM M. RAPP.
